UNITED STATES PATENT OFFICE.

WILMER STANLEY SNOW, OF OAK PARK, ILLINOIS, ASSIGNOR TO H. A. PROVOST, OF CHICAGO, ILLINOIS.

DESIGN FOR A BRIDGE ARM FOR LAMPS.

Application filed November 3, 1923. Serial No. 7,675. Term of patent 3½ years.

To all whom it may concern:

Be it known that I, WILMER STANLEY SNOW, a citizen of the United States, residing at Oak Park, in the county of Cook and State of Illinois, have invented a new, original, and ornamental Design for a Bridge Arm for Lamps, of which the following is a specification, reference being had to the accompanying drawing, forming part thereof.

The figure is a face view of the pedestal end portion of a bridge arm for lamps, the pedestal and a further portion of the arm broken away being indicated by dotted lines.

I claim:

The ornamental design for a bridge arm for lamps as shown.

WILMER STANLEY SNOW.
